S. ORENSTEIN.
WARDROBE TRUNK.
APPLICATION FILED APR. 18, 1921.

1,421,294.

Patented June 27, 1922.

UNITED STATES PATENT OFFICE.

SAMUEL ORENSTEIN, OF NEWARK, NEW JERSEY.

WARDROBE TRUNK.

1,421,294.

Specification of Letters Patent. Patented June 27, 1922.

Application filed April 18, 1921. Serial No. 462,304.

To all whom it may concern:

Be it known that I, SAMUEL ORENSTEIN, a citizen of the United States, and a resident of Newark, county of Essex and State of New Jersey, have invented certain new and useful Improvements in Wardrobe Trunks, of which the following is a specification.

This invention relates to an improved wardrobe trunk, and particularly to a closure 10 for the open side of that part of a wardrobe trunk which is equipped with clothes hangers and is substantially an open compartment into which clothing is suspended from such hangers.

15 The invention is also designed to provide a trunk in which the closure, which is preferably in the form of a flexible curtain, is secured in position so that it provides for keeping out dust, but which can be easily removed and rolled up or otherwise disposed of so that it can occupy a small space when it is not desired that it be in place.

The invention further resides in a closure which consists partly of a holder for foot-wear, which holder is in the form of a board which, when not used for holding footwear, is substantially flat on the inner face, since the shoe-holding compartments on such face are made up of compressible pockets or loops, 25 this shoe-board being sometimes utilized to form part of the closure in conjunction with the curtain aforesaid, and further being preferably arranged so that it can be removed easily so as to permit the whole front 30 of the trunk to be open, and the shoe board can be suspended on a wall or against some piece of furniture as a rack when not used in conjunction with the curtain.

The invention is illustrated in the accompanying drawing, in which Figure 1 is a front view of a trunk with the two members thereof swung apart to show the improved construction. Figure 2 is a perspective view of a curtain used in the trunk. Figure 3 is 45 a detail section taken through line 3 in Figure 1. Figure 4 is a perspective view of the lower corner of the trunk with the shoe-board swung to an open position, and Figure 5 is a detail view of two members that make 50 up a form of hinge which permits the ready removal of the shoe-board.

The structure of the trunk itself is that of any usual wardrobe trunk, and I illustrate the two trunk members 10 and 11 which 55 are adapted to be swung apart to give access to the inside of the trunk. The part 11 is

usually provided with drawers 12, the other member 10 being provided with hangers and similar means for suspending clothing within the compartment in the member 10, these 60 details being omitted from the drawing as they are the ordinary fixtures in the usual wardrobe trunk.

The top 13 of the trunk is in some types fixed and in others can be swung up and 65 backward as a lid, this open position being illustrated in dotted outline in Figure 1. The member 10 has an open side through which the clothes are inserted into the wardrobe, and in order to close said side and to 70 prevent the entrance of dust and dirt within the compartment, I provide a curtain 14, which curtain is arranged so that it can be removed from the front of the member 10.

The curtain 14 is usually made of flexible 75 material, and usually heavy material, so that the dust will not pass through it, plush or similar material being well adapted for the purpose, and I provide on the top of said curtain means for securing it in position, the 80 form shown comprising ears 15 which are bent at right angles to provide lips 16 on their ends, these being adapted to slip in between the front board 17 of the top 13 and the metal strip 18 which passes along the 85 front edge of the top wall of the compartment within the member 10, which top wall usually forms the bottom of the cover 13, and as this is usually lined with a heavy material, such as plush or felt, shown at 19, 90 the ears 15 can be slid in between the top wall of the compartment and the strip 18, as will be clearly seen from Figure 3. The friction on the material holds the lips 16 in position, the ears 15 having the plate 20 95 which is fastened, as by rivets 21, to the top part of the curtain.

In the usual form of closure I also utilize a shoe board 21 which is arranged to swing on one edge, preferably the outer edge, 100 of the open side of the member 10. A hinge composed of a knuckle 22 and a knuckle 23 formed with a pin 24 provides a convenient hinge and one which permits the easy removal of the shoe board by simply lifting 105 it, and the shoe board can then be hung up somewhere else with the inner face outward so as to give easy access to footwear supported on the board. The said inner face has a series of loops or pockets which are 110 easily compressible to provide a normally flat board, but being extensible to permit the

insertion of footwear. A latch 26 holds the shoe board shut when it is in the trunk.

The top part of the board and the bottom part of the curtain have means for connecting them to form a complete closure. In the drawing I show hooks 27 on the board, over which the rings 28 are hooked, the rings being usually arranged on the ends of elastic bands 29. Other forms, such as the snaps 10 used on automobile curtains, may be employed for holding down the curtain.

When a trunk is opened and the user is to leave the clothes in the trunk, the curtain 14 is kept in position, whereby dust is kept 15 out and the appearance of the trunk improved. When the clothes are to be removed or to be easily accessible, the curtain is unhooked at the bottom and the ears 15 at the top slide out and the curtain can be rolled 20 or folded and stored in the trunk. When the curtain and the shoe board are both removed, the whole front of the member 10 is open and clothing can be smoothly and easily placed in the trunk or removed there- 25 from.

Minor changes can be made in the details of construction without departing from the scope of my invention.

I claim:

30 1. A wardrobe trunk comprising two members hinged together, one of said members

having an open side, a flexible curtain, a strip on the bottom of the front edge of the top wall, clips on the curtain and adapted to slide between the wall and the strip, and 35 means for detachably securing the bottom of the curtain.

2. A wardrobe trunk comprising two members hinged together, one of said members having an open side, a flexible curtain, a 40 strip on the bottom of the front edge of the top wall, clips on the curtain and adapted to slide between the wall and the strip, a shoe holder filling the open side at the bottom thereof, and means for securing the bottom of the curtain to the shoe holder. 45

3. A wardrobe trunk comprising two members hinged together, one of said members having an open side, a flexible curtain, a strip on the bottom of the front edge of the 50 top wall, clips on the curtain and adapted to slide between the wall and the strip, a board swinging at one side on the edge of the open side and adapted to close the bottom part of the open side, the board having 55 means on its inner face for supporting footwear, and means for securing the bottom of the curtain to the board.

In testimony that I claim the foregoing, I have hereto set my hand, this 16th day of April, 1921. 60

SAMUEL ORENSTEIN.
